UNITED STATES PATENT OFFICE.

SAMUEL V. KENNEDY AND CHARLES S. SHARP, OF AUBURN, NEW YORK,
ASSIGNORS, BY MESNE ASSIGNMENTS, TO INTERNATIONAL HARVE-
TER COMPANY, A CORPORATION OF NEW JERSEY.

MOWER.

No. 807,385.

Specification of Letters Patent.

Patented Dec. 12, 1905.

Application filed April 2, 1903. Serial No. 150,850.

To all whom it may concern:

Be it known that we, SAMUEL V. KENNEDY and CHARLES S. SHARP, of Auburn, in the county of Cayuga and State of New York, 5 have invented a certain new and useful Mower, of which the following is a specification.

Our invention has for its object the production of a mowing-machine which is particularly simple in construction and highly efficient in operation; and to this end it consists in the novel combinations and constructions hereinafter set forth, and pointed out in the claims.

In describing this invention like characters 15 refer to corresponding parts in all the views.

Figure 1 is a side elevation, partly broken away, of a preferable embodiment of our invention. Fig. 2 is a front elevation of parts 20 of the mowing-machine seen in Fig. 1. Fig. 3 is a side elevation of a portion of said mowing-machine, the movable parts being shown in their normal position. Fig. 4 is a side elevation of a number of the parts illustrated in Fig. 3. Figs. 5 and 6 are additional side elevations of the means seen in Fig. 3, the operating-lever and parts coöperating therewith being shown in different positions. Fig. 7 is 25 an elevation of the inner face of the operating-lever. Fig. 8 is an inverted plan of parts 30 of the rear portion of our mowing-machine.

In the illustrated preferable embodiment of our invention, 1 represents the main frame, 2 the coupling-frame, 3 the finger-bar, 4 the cutter-bar, 5 the driving shaft or axle, and 6 35 the power-transmitting mechanism for actuating the cutter-bar, all of which parts are of any desirable form, size, and construction.

7 is a primary lever having its intermediate portion journaled on the main frame, its 40 rear end formed with a slot 8, its front end suitably connected to the finger-bar 3 for elevating the free end thereof, and the upper edge of its intermediate portion provided with front and rear shoulders 9 10, arranged sub- 45 stantially radially to the axis of the primary lever 7, the rear shoulder 10 being normally disposed at the rear of engaging means of the operating-lever in position to coöperate therewith, and the outer end of the front shoulder 50 9 being arranged nearer the axis of the lever 7 than the outer end of the rear shoulder 10 and being movable beneath and to the rear of said engaging means. The connections between

the finger-bar 3 and the lever 7 are here illustrated as substantially arc-shaped bearing- 55 segments 11 12, fixed together one in advance of the other and journaled on any desirable part of the coupling-frame 2, and oppositely-extending flexible connections 13 14, having their contiguous ends suitably fixed to the 60 segments 11 12 and movable over the peripheries thereof, and their other ends respectively connected to the inner end of the finger-bar 3 and the front end of the primary lever 7. As best seen in Fig. 2, the portion of the 65 periphery of the bearing-segment 11, normally engaged with the connection 13, is generally flattened for causing a minimum elevation of the free end of the cutter-bar during the initial movement of the primary lever 7. 70

A spring 15 is connected at its front extremity to the primary lever 7 and at its rear extremity to the free or lower end of an arm 16, pivoted at its upper end to the main frame 1 at the rear of the axis of the primary lever 75 7 and provided with means, as a set-screw 17, engaging the main frame 1, for adjusting the free end of the arm 16 relatively to the contiguous portion of the main frame, and thereby varying the tension of the spring 15. 80

18 19 are respectively operating lever and shaft for varying the position of the primary lever 7. The operating-lever 18 is suitably journaled on the main frame 1 on substantially the same axis as the primary lever, being shown as mounted on a hub concentric with the pivot connecting the primary lever to the main frame and as having its journal-opening 20 receiving said hub elongated vertically. Said operating-lever 18 is provided 85 with engaging means 21 22, projecting from opposite sides thereof, the means 21 coöperating with the shoulders 9 10 of the primary lever and the means 22 coöperating with separated engaging faces 23, which are provided 90 on a fixed cam or segment 24, and extend about the axis of the lever 18, and are formed with upward extensions 25 at their front ends. We also provide the lever 18 with a bearing-face 26 and a fixed shoulder 27 and hold the 100 lever in position by a locking-bolt 28, Fig. 7, reciprocally movable on said lever into and out of engagement with teeth on the cam or segment 24. The operating-shaft 19 is journaled on the main frame 1 and is provided 105 with a foot-lever 29 and with a crank-arm 30,

pivoted to the rear end of a link 31, having its front end movable in the slot 8 of the primary lever 7 and coöperating with the front end wall of said slot.

- 5 32 33 are clutch-sections which are interposed between the driving shaft or axle 5 and the power-transmitting mechanism 6, are normally engaged with each other by a spring 34, and are withdrawn from engagement by 10 any desirable connections actuated by the operating-lever 18. One of the clutch-sections 32 is normally fixed to a gear forming part of the power-transmitting mechanism 6 and loosely mounted on a shaft 35, suitably connected to the driving shaft or axle 5, and the other clutch-section 33 is connected to the shaft 35 by a key (not illustrated) and is movable lengthwise on said shaft toward and away from the clutch-section 32 by a rod 36, 15 which is provided at one end with a fork engaging the clutch-section 33, is encircled by the spring 34, and is provided at its other end with a longitudinally-adjustable shoulder 37.
- 20 25 The connections between the clutch-section 33 and the operating-lever 18 consist of the rod 36, a movable part 38, pivoted to the frame 1 and having an arm normally engaged with the shoulder 37, a longitudinally-adjustable 30 link 39, connected to the movable part 38, and an engaging member 40, having its lower end pivoted to the front end of the link 39, its upper end pivoted to the main frame 1, and its rear face arranged in the path of the face 26 of the lever 18.

35 The connections for separating the clutch-sections 32 33 are held in their position assumed when holding the clutch-sections separated by a latch 41, having its rear end supported upon and pivoted to the movable part 38 and its front end normally supported by an upper face of a shoulder 42, rigid with the frame 1 and provided with a shoulder 43, which engages the front face of the shoulder 42 and holds the latch in its operative position. When said latch is in operative position engaged with the front face of the shoulder 42, its front end lies in the path of the shoulder 27 of the operating-lever 18.

40 45 50 In the operation of our mowing-machine the free end of the cutter-bar may be raised by depressing the upper end of the foot-lever 29 and causing the front end of the link 31 to coöperate with the front end wall of the slot 8 to rock the primary lever 7 from its position shown in Fig. 3 to that illustrated in Fig. 6, or, if desired, with the primary lever in its normal position, the free end of the operating-lever may be drawn backwardly, thus engaging 55 60 65 the means 21 with the rear shoulder 10 and rocking the lever 7 to its position seen in Fig. 5. During the complete rearward movement of the operating-lever the face 26 encounters the engaging member 40 and moves the same forwardly, thus actuating the parts

40, 39, 38, and 36 to effect the separation of the clutch-sections 32 33 and moving the latch 41 forwardly and permitting the same to engage the front face of the shoulder 42 and hold the relatively movable clutch-section in its inoperative position separated from the section 32. After the foot-lever 29 has been operated to move the primary lever to the position shown in Fig. 6 and to partially elevate the free end of the cutter-bar the lever 18 may be actuated to additionally move said primary lever and elevate the free end of the cutter-bar, this movement being effected by the engagement of the means 21 with the front shoulder 9 of the primary lever 7. The elongated journal-opening of the operating-lever 18 permits of an endwise downward movement of said lever 18 to facilitate the engagement of its means 21 with either of the shoulders 9 10, and the engaging means 22 cooperates with the extensions 25 of the separated faces 23 of the cam 24 to cause said lever to move downwardly during its initial backward movement and upwardly at the end of its forward movement. As the operating-lever 18 assumes its normal position the upward endwise movement of said lever separates the face 26 from the engaging member 40, which is held in its forward position by the latch 41, and just before said lever assumes its normal position the shoulder 27 encounters the front end of the latch 41, disengaging the shoulders 43 42, whereupon the spring 34 quickly returns the parts 36, 38, 39, and 40 independently of the operating-lever 18 and effects an immediate engagement of the clutch-sections 32 33 with each other, thus avoiding breakage of the parts and adding to the efficiency and practicability of our machine.

The construction and operation of this mowing-machine will now be readily understood upon reference to the foregoing description and the accompanying drawings, and it will be noted that more or less change may be made in the component parts thereof without departing from the spirit of our invention.

Having thus fully described our invention, what we claim as new, and desire to secure by Letters Patent, is—

1. In a mower, the combination of a main frame, a coupling-frame, a finger-bar, an operating-lever journaled on the main frame and having engaging means, a primary lever journaled on substantially the same axis as the operating-lever and having front and rear shoulders arranged substantially radially to the axis of the primary lever, the rear shoulder being normally arranged at the rear of the engaging means of the operating-lever in position to coöperate therewith, and the outer end of the front shoulder being arranged nearer the axis of the primary lever than the outer end of the rear shoulder and being movable beneath said engaging means, a spring connecting the primary lever and the main

frame, means for moving the primary lever independently of the operating-lever and thereby moving the front shoulder of the primary lever beneath and at the rear of the engaging means of the operating-lever, and a cam for moving the operating-lever downwardly during the initial rearward movement of its upper end and arranging the engaging means of said lever in position to coöperate with the front shoulder of the primary lever when said front shoulder is at the rear of said engaging means, substantially as and for the purpose described.

2. In a mower, the combination of a main frame, a coupling-frame, a driving-shaft, power-transmitting mechanism for actuating the cutter-bar, clutch-sections connected, respectively, to the driving-shaft and power-transmitting mechanism, one clutch-section being movable relatively to the other into operative position, a spring for normally engaging the clutch-sections with each other, an operating-lever, movable connections between the relatively movable clutch-section and the operating-lever for disengaging the clutch-sections, and means associated with said connections for preventing the engagement of the clutch-sections by the spring until after the finger-bar has been lowered a predetermined distance, substantially as and for the purpose described.

3. In a mower, the combination of a main frame, a coupling-frame, a finger-bar, a cutter-bar, a driving-shaft, power-transmitting mechanism for actuating the cutter-bar, clutch-sections connected, respectively, to the driving-shaft and power-transmitting mechanism, one clutch-section being movable relatively to the other into an inoperative position, a spring for normally engaging the clutch-sections with each other, an operating-lever, movable connections between the relatively movable clutch-section and the operating-lever for disengaging the clutch-sections, a latch associated with said connections for preventing the engagement of the clutch-sections by the spring, said latch being movable into operative position when said relatively movable clutch-section is being moved out of operative position, a fixed shoulder coöoperating with the latch for holding the relatively movable clutch-section in its inoperative position, and a knock-off pin provided on the operating-lever for forcing the latch out of its operative position after the finger-bar has been lowered a predetermined distance, substantially as and for the purpose set forth.

4. In a mower, the combination of a main frame, a coupling-frame, a finger-bar, a cutter-bar, a driving-shaft, power-transmitting mechanism for actuating the cutter-bar, clutch-sections connected, respectively, to the driving-shaft and power-transmitting mechanism, one clutch-section being movable relatively to the other into an inoperative position, a spring

for normally engaging the clutch-sections with each other, an operating-lever, movable connections between the relatively movable clutch-section and the operating-lever for disengaging the clutch-sections, a latch connected to the relatively movable clutch-section for preventing the engagement of the clutch-sections by the spring, said latch being movable by the operating-lever into operative position when the finger-bar has been lowered a predetermined distance, means coöoperating with the latch for holding the relatively movable clutch-section in its inoperative position, and means movable with the operating-lever for forcing the latch from operative position during the return movement of said lever, substantially as and for the purpose specified.

5. In a mower, the combination of a main frame, a coupling-frame, a finger-bar, an operating-lever journaled on the main frame and having engaging means, a primary lever journaled on substantially the same axis as the operating-lever and having front and rear shoulders arranged substantially radially to the axis of the primary lever, the rear shoulder being normally arranged at the rear of the engaging means of the operating-lever in position to coöperate therewith, and the outer end of the front shoulder being arranged nearer the axis of the primary lever than the outer end of the rear shoulder and being movable beneath said engaging means, a movable arm supported by the main frame at the rear of the axis of the primary lever, means for varying the position of the arm relatively to the contiguous portion of the main frame, a spring connecting the primary lever and the arm, means for moving the primary lever independently of the operating-lever and thereby moving the front shoulder of the primary lever beneath and at the rear of the engaging means of the operating-lever, and a cam for moving the operating-lever downwardly during the initial rearward movement of its upper end and arranging the engaging means of said lever in position to coöperate with the front shoulder of the primary lever when said front shoulder is at the rear of said engaging means, substantially as and for the purpose specified.

6. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, an operating-lever, movable means between the relatively movable clutch-section and the operating-lever for disengaging the clutch-sections, a latch, means coöperating with the latch for holding the relatively movable clutch-section in inoperative posi-

tion, and means for forcing the latch from operative position, substantially as and for the purpose specified.

7. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, an operating-lever, movable means between the relatively movable clutch-section and the operating-lever for disengaging the clutch-sections, a latch supported by said movable means, means coöperating with the latch for holding the relatively movable clutch-section in inoperative position, and means for forcing the latch from operative position, substantially as and for the purpose set forth.

8. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, an operating-lever, movable means between the relatively movable clutch-section and the operating-lever for disengaging the clutch-sections, said means being movable independently of the operating-lever to permit the spring to engage the clutch-sections with each other, a latch supported by the movable means for holding said means in its position assumed when the clutch-sections are disengaged, means coöperating with the latch for holding the relatively movable clutch-section in inoperative position, and means for forcing the latch from operative position, substantially as and for the purpose described.

45 9. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, an operating-lever, movable means between the relatively movable clutch-section and the operating-lever for disengaging the clutch-sections, a latch supported by said movable means, means coöperating with the latch for holding the relatively movable clutch-section in inoperative position, and means fixed to the operating-lever for forcing the latch from operative position, substantially as and for the purpose described.

60 10. In a mower, the combination of a main frame, a coupling-frame, a finger-bar, a cutter-

bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, a shoulder rigid with the main frame, an operating-lever, movable means between the relatively movable clutch-section and the operating-lever for disengaging the clutch-sections, a latch coacting with said shoulder rigid with the frame for holding the relatively movable clutch-section in inoperative position, and means for forcing the latch from operative position, substantially as and for the purpose set forth.

11. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, a shoulder rigid with the main frame, an operating-lever, movable means between the relatively movable clutch-section and the operating-lever for disengaging the clutch-sections, a latch having its rear end supported by said movable means and its front end normally supported by said shoulder and movable into operative engagement therewith when the operating-lever disengages the clutch-sections, and means for forcing the latch from operative position, substantially as and for the purpose specified.

12. In a mower, the combination of a main frame, a coupling-frame, a finger-bar, a cutter-bar, a driving-shaft, power-transmitting mechanism for actuating the cutter-bar, clutch-sections connected respectively to the driving-shaft and power-transmitting mechanism, one clutch-section being movable relatively to the other into an inoperative position, a spring for normally engaging the clutch-sections with each other, a shoulder rigid with the main frame, an operating-lever, movable means between the relatively movable clutch-section and the operating-lever for disengaging the clutch-sections, a latch having its rear end supported by said movable means and its front end normally supported upon an upper face of said shoulder and movable into engagement with a front face thereof when the operating-lever disengages the clutch-sections, and means fixed to the operating-lever for elevating the front end of the latch out of engagement with said front face of the shoulder rigid with the main frame, substantially as and for the purpose set forth.

13. In a mower, the combination of a main frame, a coupling-frame, a finger-bar, a cutter-bar, a driving-shaft, power-transmitting

mechanism for actuating the cutter - bar, clutch-sections connected respectively to the driving-shaft and power-transmitting mechanism, one clutch-section being movable relatively to the other into an inoperative position, a spring for normally engaging the clutch-sections with each other, a movable part pivoted to the main frame and connected to the relatively movable clutch-section, an operating-lever having means for actuating the movable part to disengage the clutch-sections, a latch, means coöperating with the latch for holding the relatively movable clutch-section in inoperative position, and means for forcing the latch from operative position, substantially as and for the purpose described.

14. In a mower, the combination of a main frame, a coupling-frame, a finger-bar, a cutter-bar, a driving-shaft, power-transmitting mechanism for actuating the cutter - bar, clutch-sections connected respectively to the driving-shaft and power-transmitting mechanism, one clutch-section being movable relatively to the other into an inoperative position, 25 a rod connected to the relatively movable clutch-section and provided with an adjustable shoulder, a spring for normally engaging the clutch-sections with each other, a movable part pivoted to the main frame and having an 30 arm normally engaged with the adjustable shoulder on the rod, a shoulder rigid with the main frame, an operating-lever connected to the movable part for actuating the same to disengage the clutch-sections, a latch having 35 its rear end supported by the movable part and its front end normally supported by the latter shoulder and movable into operative engagement therewith when the operating-lever actuates the movable part to disengage 40 the clutch-sections, and means for forcing the latch from operative position, substantially as and for the purpose set forth.

15. In a mower, the combination of a main frame, a coupling-frame, a finger-bar, a cutter-bar, a driving-shaft, power-transmitting mechanism for actuating the cutter - bar, clutch-sections connected respectively to the driving-shaft and power-transmitting mechanism, one clutch-section being movable relatively to the other into an inoperative position, 45 a rod connected to the relatively movable clutch-section and provided with an adjustable shoulder, a spring for normally engaging the clutch-sections with each other, a movable 50 part pivoted to the main frame and having an arm normally engaged with the adjustable shoulder on the rod, a shoulder rigid with the main frame, an operating-lever connected to the movable part for actuating the same to 55 disengage the clutch-sections, a latch having its rear end supported by the movable part and its front end normally supported upon an upper face of the latter shoulder and movable into engagement with a front face thereof 60 65 when the operating-lever actuates the mov-

able part to disengage the clutch-sections, and means fixed to the operating-lever for elevating the front end of the latch out of engagement with said front face of the latter shoulder, substantially as and for the purpose described.

16. In a mower, the combination of a main frame, a coupling-frame, a finger-bar, a cutter-bar, a driving-shaft, power-transmitting mechanism for actuating the cutter - bar, 70 clutch-sections connected respectively to the driving-shaft and power-transmitting mechanism, one clutch-section being movable relatively to the other into an inoperative position, a rod connected to the relatively movable clutch-section and provided with an adjustable shoulder, a spring for normally engaging the clutch-sections with each other, an operating-lever, means between the adjustable shoulder and the operating-lever for disengaging the clutch-sections, a latch, means coöperating with the latch for holding the relatively movable clutch-section in inoperative position, and means for forcing the latch from operative position, substantially as and for 80 the purpose specified.

17. In a mower, the combination of a main frame, a coupling-frame, a finger-bar, a cutter-bar, a driving-shaft, power-transmitting mechanism for actuating the cutter - bar, 85 clutch-sections connected respectively to the driving-shaft and power-transmitting mechanism, one clutch-section being movable relatively to the other into an inoperative position, a spring for normally engaging the 90 clutch-sections with each other, a movable part pivoted to the main frame and connected to the relatively movable clutch-section, an operating-lever connected to the movable part for actuating the same to disengage the clutch-sections, a latch supported by the movable part and movable therewith into operative position, means coöperating with the latch for holding the relatively movable clutch-section in inoperative position, and means for forcing 95 the latch from operative position, substantially as and for the purpose described.

18. In a mower, the combination of a main frame, a coupling-frame, a finger-bar, a cutter-bar, a driving-shaft, power-transmitting 100 mechanism for actuating the cutter - bar, clutch-sections connected respectively to the driving-shaft and power-transmitting mechanism, one clutch-section being movable relatively to the other into an inoperative position, a spring for normally engaging the 105 clutch-sections with each other, a movable part pivoted to the main frame and connected to the relatively movable clutch-section, an operating-lever connected to the movable part 110 for actuating the same to disengage the clutch-sections, a latch supported by the movable part and movable therewith into operative position, means coöperating with the latch for holding the relatively movable clutch-section 115 120 125 130

in inoperative position, and means fixed to the operating-lever for forcing the latch from operative position, substantially as and for the purpose specified.

- 5 19. In a mower, the combination of a main frame, a coupling-frame, a finger-bar, a cutter-bar, a driving-shaft, power-transmitting mechanism for actuating the cutter-bar, clutch-sections connected respectively to the 10 driving-shaft and power-transmitting mechanism, one clutch-section being movable relatively to the other into an inoperative position, a spring for normally engaging the clutch-sections with each other, an operating-lever journaled on the main frame and having engaging means, a primary lever journaled on substantially the same axis as the operating-lever and having front and rear shoulders arranged substantially radially to the axis of the primary lever, the rear shoulder being normally arranged at the rear of the 15 engaging means of the operating-lever in position to coöperate therewith, and the outer end of the front shoulder being arranged nearer the axis of the primary lever than the outer end of the rear shoulder and being movable beneath said engaging means, means for moving the primary lever independently of said operating-lever and thereby moving the 20 front shoulder of the primary lever beneath and at the rear of the engaging means of the operating-lever, a cam for moving the operating-lever downwardly during the initial rearward movement of its upper end and arranging the engaging means of said lever in 25 position to coöperate with the front shoulder of the primary lever when said front shoulder is at the rear of said engaging means, movable means between the relatively movable clutch-section and the operating-lever for disengaging the clutch-sections, said means being movable independently of the operating-lever to permit the spring to engage the 30 clutch-sections with each other, a latch supported by the movable means for holding said means in its position assumed when the clutch-sections are disengaged, means coöoperating with the latch for holding the relatively movable clutch-section in inoperative position, and means for forcing the latch from operative position, substantially as and for the purpose set forth.
- 40 20. In a mower, the combination of a main frame, a coupling-frame, a finger-bar, a cutter-bar, a driving-shaft, power-transmitting mechanism for actuating the cutter-bar, clutch-sections connected respectively to the 45

driving-shaft and power-transmitting mechanism, one clutch-section being movable relatively to the other into an inoperative position, a spring for normally engaging the clutch-sections with each other, an operating-lever journaled on the main frame and having engaging means, a primary lever journaled on substantially the same axis as the operating-lever and having front and rear shoulders arranged substantially radially to the axis of the primary lever, the rear shoulder being normally arranged at the rear of the 50 engaging means of the operating-lever in position to coöperate therewith, and the outer end of the front shoulder being arranged nearer the axis of the primary lever than the outer end of the rear shoulder and being movable beneath said engaging means, means for moving the primary lever independently of said operating-lever and thereby moving the front shoulder of the primary lever beneath and at the rear of the engaging means of the 55 operating-lever, a cam for moving the operating-lever downwardly during the initial rearward movement of its upper end and arranging the engaging means of said lever in position to coöperate with the front shoulder of the primary lever when said front shoulder is at the rear of said engaging means, movable means between the relatively movable clutch-section and the operating-lever for disengaging the clutch-sections, said means being movable independently of the operating-lever to permit the spring to engage the 60 clutch-sections with each other, a latch supported by the movable means for holding said means in its position assumed when the clutch-sections are disengaged, means coöoperating with the latch for holding the relatively movable clutch-section in inoperative position, and means for forcing the latch from operative position, substantially as and for the purpose set forth.

In testimony whereof we have hereunto signed our names, in the presence of two attesting witnesses, at Auburn, in the county of Cayuga, in the State of New York, this 30th day of March, 1903.
